TELEPHONE SYSTEM

Fritz Pfleiderer, Berlin-Wilmersdorf, and Bernhard Seiffert, Berlin-Charlottenburg, Germany, assignors to Siemens & Halske Aktiengesellschaft, Wernerwerk, Siemensstadt, near Berlin, Germany

Application October 13, 1937, Serial No. 168,836
In Germany October 14, 1936

3 Claims. (Cl. 178—44)

The subject of the invention is a circuit arrangement for remote communication systems and in particular telephone systems, which serves the purpose of selectively blocking or permitting the transmission of alternating currents, and in particular speech currents, over a line during the establishment or during the existence of a call at a desired stage of the call.

This is achieved in that dry-plate rectifiers 10 are arranged in the remote communication line and block the line as regards the transmission of alternating currents such as for example speech currents or release it in dependence upon the mode of their connection to the leads of the 15 line (series or shunt connection) and in dependence upon whether they are traversed by direct current or not.

It is known in pay station telephones for example to prevent speech currents passing from 20 the calling subscriber to the called subscriber before the former has paid the full fee for the call. This is effected by devices at the pay station or in the exchange for example by blocking the microphone by means of valves and in other 25 ways.

In systems with speech amplifiers and in loud speaker systems so-called echo suppressors are known which for example when sending speech 30 block the receiving circuit and when receiving block the sending circuit in order to prevent the known echo and back coupling effects. These devices consist for the most part of thermionic tubes which effect the blocking in one or other speech direction by relays disposed in their anode 35 circuits.

Moreover, in systems having lines equipped with amplifiers devices are known which serve to allow the signal receiving means provided at the amplifiers of the individual sections of the 40 line only to respond to alternating currents in a particular direction this being effected for example by bridge circuits and in other ways.

The arrangement according to the invention 45 is differentiated from these known arrangements by the manner in which the blocking or release of the lines for the flow of speech currents is effected. This mode of achieving the desired result differs from the known arrangements on account of its great simplicity, considerable greater 50 efficiency and smaller production and maintenance cost.

The invention will now be described in greater detail with reference to the embodiments shown 55 in the drawings. The embodiment according to

Figs. 1-2 shows the application of the principle of the invention to a pay station system and Fig. 3 shows the application to a loud speaker system. Fig. 4 shows the resistance characteristic of a rectifier.

The direct current J flowing through the rectifier is represented by the abscissae and the ordinates represent the corresponding impedance R. Only those devices which are necessary to enable the invention to be understood are represented and described.

The possibilities of the application of the invention are not limited to the embodiments shown but may be used also for various other purposes arising in remote communication systems and telephone systems such as for example the temporary coupling and differential influencing of impulse repeaters, registers and the like.

In the embodiment according to Fig. 1 it is assumed that of the speech currents transmitted 20 to the subscribers connected to the two lines L1 and L2 only that from subscriber T2 can pass unimpeded to subscriber T1 while the transmission of speech currents proceeding from subscriber T1 to subscriber T2 is normally blocked. Subscriber T1 may be assumed to be the calling party and calls from the pay station while subscriber T2 calls from a normal subscriber's station. The calling subscriber T1 will be prevented, 25 so long as he has not paid the full fee, i. e., has not inserted it in the pay station collecting device (not shown), from conversing with the called subscriber. So long as he has not paid the full fee he can hear the called party as soon as the latter replies but his own speech is not transmitted to the called party.

For this purpose metal dry-plate rectifiers are incorporated in the leads of the line in the exchange as a blocking means. The dry-plate rectifiers possess a high resistance to the speech 40 currents i. e., weak alternating currents but when a direct current which is relatively large in proportion to the amplitude of the alternating current traverses the rectifier the resistance of the latter is reduced by a certain amount as is indicated in Fig. 4 and increases again immediately to its high value when the direct current flow ceases.

In Fig. 1 the rectifiers are represented by G1 50 and G2. So long as no direct current flows through them, i. e., in the normal condition, they block the passage of speech currents from the one subscriber to the other over the lines L1 and L2 in both directions. In order now to enable 55

the calling subscriber to know whether his call has been completed to the called party he must hear the speech of the called party when the latter replies and therefore the blocking of the 5 called parties' speech must be removed.

This is done in the following way: On the side of the blocking rectifiers $G1$ and $G2$ nearest to the called subscriber a device is arranged which consists of a full wave rectifier $G1$ and for example 10 of dry-plate rectifiers arranged in a four-armed bridge and an arrangement of coils or a filter circuit Spl and has its input side (alternating current circuit) connected over a repeater Ue to the leads of the line and is connected over 15 its output side (direct current circuit) directly for example by conductive connection, to the leads of the line. Part of the incoming speech of the called subscriber $T2$ from the line $L2$ passes to the full wave rectifier $G1$ is here rectified 20 and the rectified speech current passes over the filter circuit Spl , lead a blocking rectifier $G1$, choke coil Dr , blocking rectifier $G2$ and back through the filter circuit Spl to the full wave rectifier $G1$. As soon as this direct current 25 flows through the blocking rectifiers $G1$ and $G2$ their resistance sinks to a low value and the speech currents can pass unimpeded to the subscriber $T1$. It may be mentioned here that if it is desired still further to increase the blocking 30 effect of the blocking rectifiers a further blocking element can be arranged in the direct current path as indicated in Figs. 1 and 4. The filter circuit Spl allows direct current to pass through unimpeded but not alternating current. As soon 35 as the calling subscriber $T1$ hears the called subscriber $T2$ who has replied he pays the requisite fee.

In a way which is not shown and which does not concern the present invention, a relay, for 40 example (not shown) is energized and at its contacts $1x$ and $2x$ shunts the blocking rectifiers $G1$ and $G2$ so that subscribers now can converse together easily. At contacts $3x$, $4x$, $5x$ and $6x$ the full wave rectifier $G1$ is disconnected for the 45 remainder of the call. At the end of the call the relay releases again and its contacts $1x$ to $6x$, inclusive, reassume their normal position. Since the dry-plate rectifiers possess no mechanical parts they operate completely without inertia 50 so that all the operations take place rapidly and without any delay. If the rectifier $G1$ is disposed on the other side of the blocking rectifiers $G1$ and $G2$ the speech currents passing 55 from the direction $L1$ would be able to pass to $L2$ while the speech currents coming from $L2$ would at first be blocked.

The embodiment according to Fig. 2 is different from that in Fig. 1 only in that the input of 60 the full wave rectifier $G1$ i. e., its coupling transformer Ue' is not directly connected to the line but is inductively coupled to it by means of the choke-coil $Dr1$, and the output passes over the point of symmetry between the choke-coils 65 $Dr1$ and $Dr2$ simultaneously over both leads of the line. Since in this embodiment the same references are used as in Fig. 1 the operation may be understood from the description and drawing of the latter embodiment.

70 The embodiment according to Fig. 3 shows the application of the principle of the invention to loud speaker systems. The drawing shows a subscriber's station $T1$ connected to the line L together with the loud speaker L , microphone M 75 and the associated devices. At the other end of

the line L is situated a similar subscriber's station.

In such systems the acoustic coupling i. e., the distortion produced by the effect of the sound waves proceeding from the loud speaker 5 on the microphone must be prevented. This is realized in that the blocking rectifiers are arranged in the branch circuit for transmitting speech currents in series with the leads of the line and are arranged in the receiving branch of 10 the station circuit across the leads of the line (shunt arrangement).

The mode of operation of the arrangement shown in Figure 3 will now be described. The speech currents arising when the microphone M 15 is taken into use are impressed on the grid of the amplifying tube $V1$ by way of the transformer Uem and are thereby amplified. The amplified speech currents pass over the transformers $Ue1$ and $Ue2$ in the branch circuit I for the 20 outgoing speech currents. In this branch is disposed the blocking rectifier $G1$. So long as no direct current flows over the rectifier the speaking currents are prevented from passing over the repeater Ueg in the line L to the distant 25 subscriber on account of the high resistance of the rectifier and the consequent high attenuation of this branch of the line. In order now to permit the uninterrupted flow of the speech currents completely automatically and without any 30 operation on the part of the subscriber a portion of the speech currents is led off over a winding 3 of the transformer $Ue2$ and is impressed on the grid of the amplifying tube $V2$ and is there 35 amplified. These amplified speech currents are passed by means of the repeater $Ue3$ to a full wave rectifier $G1$ for example comprising a network of dry-plate rectifiers, are rectified and are led through the blocking rectifier $G1$ in the outgoing branch I and through the rectifier $G2$ in 40 the incoming branch II of the speaking circuit. A direct current circuit is thus set up which passes from the rectifier $G1$ out over the choke-coils $Dr3$ and $Dr1$ the blocking rectifier $G1$, the choke coil $Dr2$ and the blocking rectifier $G2$ and 45 back to the rectifier $G1$. On account of the direct current flow the high resistance of the blocking rectifier $G1$ is brought to a low value and the high attenuation in the branch circuit I is reduced so that the speech currents pass 50 unimpeded through this circuit and over the transformer Ueg of the line L and to the subscriber disposed at the other end of the line.

The transformer Ueg and the balancing element N are so arranged as to prevent speech 55 currents from the branch circuit I passing into the branch for incoming speech currents II instead of to the line L and similarly to prevent the speech currents incoming over the line L passing to the outgoing branch circuit I instead of into the branch circuit II for incoming speech currents. Since the balancing effect of these devices, the transformer and the balancing element are not always completely effective special care must be taken in the present circuit on 60 account of the high amplification to prevent the outgoing as well as incoming speech currents passing to the output point over the transformer Ueg . Since direct current is also flowing over the blocking rectifier $G2$ the impedance of this 65 rectifier to the speech currents is also reduced to a low value. The reduction of the impedance in the incoming branch circuit produced at the blocking rectifier $G2$ in contradistinction to the blocking rectifier $G1$ does not, however, produce 70 75

any reduction in the attenuation but increases the attenuation i. e., the blocking rectifier G2 operates directly as a third circuit for the alternating speech currents passing to it since it is arranged in shunt across the leads of the branch circuit II. Since the rectifiers for rectifying the alternating speech currents and their associated amplifying valves as they have no mechanically movable parts operate as a relay having no inertia, the operations described take place exceptionally rapidly and without any delay.

When now the subscriber T1 ceases to talk and the subscriber at the other end of the line L talks his speech currents incoming over the line L must be prevented from passing into the outgoing branch I instead of into the incoming branch II. When the subscriber T1 ceases to talk, the direct current flow from the rectifier G11 over the blocking rectifiers G1 and G2 also ceases immediately and these blocking rectifiers once more offer their high resistance to the speech current. Since the blocking rectifier G2 is arranged in shunt across the leads of the branch circuit II its resistance does not constitute any attenuation as regards the speech currents incoming to the branch circuit from the line L. The speech currents can, therefore, pass unimpeded over the transformer Ue4 and the transformer Ue6 to the grid of the amplifying tube V4. They are here amplified and operate on the loud speaker L. A portion of these incoming speech currents are led off over winding 3' of the transformer Ue4 and are impressed on the grid of the amplifying tube V3 and are here amplified and are passed over the transformer Ue5 to the full wave rectifier G13. The direct current flow produced is led to the grid of the microphone amplifier V1 to constitute a negative grid bias and thereby blocks this amplifier. The microphone M can no longer be influenced by the waves produced by the loud speaker L and the oscillations incoming to it are prevented from passing into the outgoing branch circuit I.

The attenuation networks formed by the blocking rectifiers in the circuit—microphone, outgoing branch of the circuit, incoming branch of the circuit, loud speaker and back to the microphone—are so chosen and arranged that the speech currents passing for example from the outgoing branch of the circuit are no longer able to operate the loud speaker. The speech currents proceeding from the line L from the distant subscriber can, however, overcome the attenuation produced by the blocking rectifier G2 when traversed by the direct current so that the distant subscriber is able to break in to the conversation. This is true also for the opposite direction and the rectifier G1. In this case also while the distant subscriber is still speaking the subscriber T1 can take over the lead in the conversation. His speech currents then overbalance the grid bias of the tube V1 produced by the additional negative grid potential from G13.

There is, therefore, no need for either of the subscribers to wait until the other subscriber ceases before commencing to talk but each subscriber is in a position to take over the lead in the conversation. In order now to avoid large variations in the sound intensity such as arise from the varying attenuation of the various lines when the microphone is used over a larger or smaller distance the speech currents from the subscriber which are led off and rectified by the rectifiers G11 and G12 are also used to effect an equalization of these variations in amplitude.

When subscriber T1 for example speaks, the direct current produced by the rectifier G11 does not only pass over the blocking rectifiers G1 and G2 but also over a further blocking rectifier G3 arranged between the transformers Ue1 and Ue2 in the outgoing branch I and since this is arranged as a bridge between the leads of the branch I brings about an increased attenuation of this circuit on account of the reduction of its high resistance so that the speech currents proceeding from the microphone are reduced in strength. On account of this reduction in strength, however, the direct current flow is also reduced in the rectifier G11 by the blocking rectifier G3 and the direct current in the rectifier G11 can increase again. This variation about a normal condition equalizes the variations in the sound intensity.

The same is true for the speech currents received over the line L from the distant subscriber. These are led off over the transformer Ue5 to a further full wave rectifier G12 and here influence the blocking rectifier G4 arranged as a bridge across the leads of the branch circuit II. The function of this latter rectifier is the same and brings about the same effect as the blocking rectifier G3 in the outgoing branch I. Thus variations in the sound intensity of the outgoing and incoming speech currents are equalized so as to insure a uniform transmission of the speech even in the case of varying attenuation in the line and other un-uniform conditions in the transmitting system.

What is claimed is:

1. In combination, a circuit for the transmission of speech currents, a volume control rectifier bridging the input end of said circuit and normally having an impedance of such value as to present substantially no blocking to incoming speech currents, a series connected rectifier in the output end of said circuit normally having an impedance of such value as to substantially block outgoing speech currents, voice controlled means responsive to speech currents at a point in said circuit intermediate to said two rectifiers and effective to cause both of said rectifiers to be traversed by direct current thereby to decrease their impedance, the blocking of the input end of said circuit increasing and the blocking of the output end decreasing responsive to a decrease in the impedance of the corresponding rectifiers.

2. In combination, a circuit for the transmission of speech currents in one direction, a second circuit for the transmission of speech currents in another direction, a volume control rectifier bridging the input end of said first circuit and normally having an impedance of such value as to present substantially no blocking to incoming speech currents, a series connected rectifier in the output end of said first circuit normally having an impedance of such value as to substantially block outgoing speech currents, a rectifier bridging the input end of said second circuit and normally having an impedance of such value as to present substantially no blocking to incoming speech currents, voice controlled means responsive to speech currents at a point in said first circuit intermediate said first two rectifiers and effective to cause all three of said rectifiers to be traversed by direct current thereby to decrease their impedance, the blocking of the input ends of both of said circuits increasing and the blocking of the output end of said first circuit decreasing.

ing responsive to a decrease in the impedance of the corresponding rectifiers.

3. In combination, a circuit for the transmission of speech currents in one direction, a second circuit for the transmission of speech currents in another direction, a volume control rectifier bridging the input end of said first circuit and normally having an impedance of such value as to present substantially no blocking to incoming speech currents, a series connected rectifier in the output end of said first circuit normally having an impedance of such value as to substantially block outgoing speech currents, a rectifier bridging the input end of said second circuit and normally having an impedance of such value as to present substantially no blocking to incoming

speech currents, voice controlled means responsive to speech currents at a point in said first circuit intermediate said first two rectifiers and effective to cause all three of said rectifiers to be traversed by direct current thereby to decrease 5 their impedance, the blocking of the input ends of both of said circuits increasing and the blocking of the output end of said first circuit decreasing responsive to a decrease in the impedance of the corresponding rectifiers, and voice 10 controlled means responsive to speech currents passing said rectifier in said second circuit for at times preventing speech currents from being impressed upon the input end of said first circuit.
